UNITED STATES PATENT OFFICE.

WYLLYS E. DOWD, JR., OF NEW YORK, N. Y., ASSIGNOR TO POWER SPECIALTY COMPANY, OF NEW YORK, N. Y., A CORPORATION OF NEW YORK.

STEAM GENERATING AND SUPERHEATING SURFACE.

Application filed March 26, 1924. Serial No. 701,915.

My present invention consists in a novel arrangement of steam superheating elements and steam generating elements adapted to be incorporated in, or to form a lining for, the wall of the combustion chamber of a furnace from which the elements absorb heat by radiation.

The use of steam generating and superheating elements as a screen or lining for a combustion chamber wall absorbing heat from the combustion chamber is desirable on account of the heat absorption efficiency and capacity of the elements, and the protection afforded against overheating and consequent destruction of the combustion chamber wall. The use of steam generating and superheater surface thus disposed is especially important in the case of superheating steam surface because of the high superheating effect which can be obtained with a small amount of such superheating surface, and the fact that the superheating effect thus obtained does not tend to increase with the boiler load, as is the case with ordinary superheaters heated wholly or mainly by contact with heating gases after the latter have been partially cooled by contact with steam generating surface. When steam superheating elements are incorporated in, or placed in front of a combustion chamber wall in which a high temperature is maintained, there is a tendency to a warping or bending of the elements as a result of the temperature differences to which the front and back sides of the elements are subjected, and the fact that such elements must be provided with thick walls to insure proper strength and durability while obtaining the desired heat transfer. The use of a lining for a combustion chamber wall formed of tubular water containing steam generating elements is restricted by the fact that, if the extent of surface provided by these elements is sufficient to adequately protect against overheating of the combustion chamber walls, their heat absorption undesirably lowers the combustion chamber temperature.

The general object of the present invention is to combine steam generating and steam superheating elements in the walls of a combustion chamber so as to avoid an undesirably large heat absorption by either set of elements while utilizing the water heating elements to resist the tendency of the superheating elements to bend in planes trans-

verse to their lengths. This I accomplish by arranging the steam superheating and water heating elements side by side alternately with respect to one another, and by mechanically connecting the superheating elements to the water heating elements. With the side by side and alternating arrangement of the two sets of elements, each set of elements screens the elements of the other set against the absorption of radiant heat to a certain extent, and reduces the amount of radiant heat which said other set absorbs as compared with the amount of heat which would be absorbed by it if the screening elements were simply omitted.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is a somewhat diagrammatic elevation of a boiler furnace;

Fig. 2 is an elevation of a portion of the heating surface lining for the combustion chamber of Fig. 1;

Fig. 3 is a partial section on the line 3—3 of Fig. 1;

Fig. 4 is a view taken similarly to Fig. 2 illustrating a modified construction;

Fig. 5 is a section of the line 5—5 of Fig. 4;

Fig. 6 is a view taken similarly to Fig. 2 illustrating a second modification;

Fig. 7 is a section on the line 7—7 of Fig. 6;

Fig. 8 is a view taken similarly to Fig. 2 illustrating a third modification;

Fig. 9 is a section on the line 9—9 of Fig. 8; and

Fig. 10 is a partial section on the line 10—10 of Fig. 7.

Fig. 1 is a somewhat diagrammatic representation of a water tube boiler furnace of conventional type comprising a bank of water tubes B located above a combustion chamber A with the tubes B connected at their ends to headers B', the upper ends of the upper headers B' being connected to a steam and water drum C by the usual hori-

horizontal circulating tubes D, while the upper ends of the lower headers B' are connected to the drum C by elongated nipples E. Incorporated in the front wall of the combustion chamber A are steam generating elements F and superheater elements G. As shown, the steam generating elements F are in the form of tubes each having its body portion surrounded by a casing formed of 10 block-like sections F' of cast iron or the like. The end portions of each element F are out-turned, the lower out-turned ends being connected to a lower header F², while the upper out-turned ends are connected to 15 a header F³. The tubular elements F and the headers F² and F³ are connected in the water circulating system of the boiler. As indicated in Fig. 1, the connections for this purpose comprise a down-comer pipe H at 20 one side of the boiler connected to the corresponding end of the header F² and conduits B³ located at the front corners of the boiler structure at opposite sides of the series of upper headers B'. Each conduit 25 B³ is connected at its lower end to the corresponding end of the header F³, and is connected at its upper end to the steam and water drum C by tubes D', which may be similar to and are alongside the circulating 30 tubes D.

The elements F are spaced apart, and in the space between each adjacent pair of elements F is located a superheater element G. Each superheater element G in the form 35 shown is made of cast steel sections connected end to end. Each element G is connected at its lower end by a transverse pipe section G' to the superheater outlet header G², and is connected at its upper end by a 40 similar transverse pipe section G' to the superheater inlet header G³. The latter is connected at one or both ends of the boiler to the steam space in the steam and water drum C by a corresponding steam pipe J.

45 As shown best in Figs. 2 and 3, the elements G are generally rectangular in cross section with a steam passage therein which is rectangular in cross section and is elongated in a direction parallel to the length of 50 the headers G² and G³. The casing blocks F' of the elements F are generally rectangular in cross section, and as shown, the elements F and G unite to form a smooth heat absorbing surface exposed to the interior of 55 the combustion chamber. The arrangement of the elements F and G to provide a smooth heat absorbing surface facilitates the removal of furnace dust depositing thereon, which may be accomplished in any suitable manner.

60 The elements F and G are provided, in accordance with the present invention, with means whereby the elements F resist the tendency of the elements G to bend or warp 65 as the result of the varying excess in tem-

perature of the front or combustion chamber side of each element G over the temperature of the back side of the element existing under varying conditions of operation. In the particular construction illustrated in 70 Figs. 2 and 3, this result is obtained by forming the elements G with ribs G⁵ which extend parallel to the combustion chamber faces of the elements G' at the rear sides of the latter, and are received in correspondingly shaped grooves or slots formed in the sides of the casing blocks F adjacent the rear faces of the latter. By thus interlocking the elements G and F in the manner described, the full strength of the latter is utilized in resisting the tendency of the elements G to warp and bend while at the same time the bodily longitudinal expansion and contraction of each of the elements G and F relative to its neighbors is permitted. In practice, the elements F may be stiffened and held against any tendency to bow with the superheater elements by suitable connections to an external framework or supporting means, shown as comprising angle bars K. The out-turned end portions of the elements F and the transverse pipe connections G' to the elements G provide the flexibility needed to accommodate the bodily longitudinal expansion and contraction of 85 the elements.

In addition to the support against bending afforded the elements G by the elements F, with which they are interlocked, the elements F absorb heat from the elements G 100 and thereby advantageously reduce the total amount of heat absorption by the latter. The set of elements F, and the set of elements G each co-operate to reduce the heat absorbed by the other set from the combustion chamber, in comparison with the amount of heat which would be absorbed by the set of elements, if the other set of elements were omitted, since each of the elements screens the side of each adjacent element against radiant heat absorption. Each element F absorbs heat from the adjacent element G and correspondingly cools the latter owing to the fact that the elements G are hotter than the elements F. 115

120 The characteristic advantages of the apparatus shown in Figs. 1, 2, and 3 can be obtained with different and simpler constructions. For example, as shown in Figs. 4 and 5, the steam generating elements FA and the steam superheating elements GA may be each in the form of a bare tube with the elements GA supported against warping by the elements FA through metallic clamping parts L and LA disposed at intervals 125 along the length of the tube elements and clamping the elements FA and GA together, each pair of clamping blocks L and LA being held together by means of a bolt F¹⁰ welded to the corresponding element FA 130

and passing through the corresponding pair of clamping blocks. In Figs. 4 and 5 the elements FA have their centers in front of the centers of the elements GA, thus increasing the extent to which the elements FA screen the elements GA against the absorption of radiant heat as compared with the arrangements shown in Figs. 6 to 9 inclusive, in which the elements FA and GA are arranged with their axes in the same plane.

In Figs. 6 and 7 the elements FA and GA are each connected at intervals along their lengths to transversely extending supports M by means of bolt-like projections F¹⁰ welded to the rear or outer sides of the elements FA as in Figs. 4 and 5, and similar bolt-like projections G¹⁰ welded to the rear or outer sides of the elements GA. Advantageously, the openings in the elements M, receiving the ends of the projections G¹⁰, are slotted in a direction parallel to the length of the elements GA to accommodate the bodily longitudinal expansion and contraction of the elements GA with respect to the elements FA.

In the construction illustrated in Figs. 8 and 9, the elements FA and GA are arranged side by side, as in Figs. 6 and 7, and each element GA is supported against warping by means of transverse metal bars or blocks O distributed along the length of the elements and each formed with openings to receive one or more of each of the elements FA and GA.

While in accordance with the statutes, I have illustrated and described the best forms of my invention now known to me, it will be

apparent to those skilled in the art that changes may be made in the form of the apparatus disclosed without departing from the spirit of my invention as set forth in the appended claims, and that certain features of my invention may sometimes be used with advantage without a corresponding use of other features.

Having now described my invention, what I regard as new and desire to secure by Letters Patent, is:

1. Steam generating and superheating apparatus comprising tubular water heating elements and super-heating elements arranged alternately along the side of a combustion chamber and absorbing heat by radiation from the latter, and mechanical connections between the elements whereby the water heating elements assist in preventing warping of the steam superheating elements, and each element tends to reduce the heat absorption by neighboring elements.

2. Steam generating and superheating apparatus comprising tubular water heating elements and superheating elements arranged alternately along the side of a combustion chamber and absorbing heat by radiation from the latter, the water heating elements and superheating elements being formed with longitudinally extending shoulders which co-operate to prevent bending of one element relative to the other.

Signed at New York city in the county of New York and State of New York this 24th day of March A. D. 1924.

WYLLYS E. DOWD, JR.
